AUTOMATIC STOP MECHANISM FOR TALKING MACHINES.

1,405,046.

Specification of Letters Patent. Patented Jan. 31, 1922.

Application filed January 18, 1916. Serial No. 72,774.

To all whom it may concern:

Be it known that I, LOUIS G. LARSEN, a citizen of Copenhagen, Denmark, and a resident of Bridgeport, Connecticut, have invented a new and useful Improvement in Automatic Stop Mechanism for Talking Machines, which invention is fully set forth in the following specification.

The present invention relates to automatic stop mechanism of the type especially designed for talking machines, and more particularly to devices of this character wherein the rotation of the rotating element or turn-table is made to stop when the traveling element or tone-arm ceases its movement across the same.

The objects of the present invention are to provide a simple, economical and efficient device of this character which may be readily installed, which will efficiently perform its stopping function when the tone-arm comes to rest, however long or short the sound-record may be, and which is so simple in construction and operation as to minimize the chances of the parts of the device becoming deranged and failing to operate.

The inventive idea is applicable without regard to the particular character of motor employed for rotating the turn-table. For the purpose of illustrating the invention, it is shown in connection with a brake mechanism which is applied to stop the turn-table when the tone-arm movement across the sound-record ceases. But the invention is equally applicable to a construction in which an electrical motor, for example, is employed for rotating the turn-table, and in which means, as for example an electrical switch, is operated to effect the stopping of the motor.

The invention will be better understood by reference to the accompanying drawings, illustrating one expression of the inventive idea, and wherein—

Fig. 1 is a side elevation of a talking machine provided with the improved device;

Fig. 2 is a top plan view, partly broken away to show the mechanism beneath the motor-board;

Fig. 3 is an inverted plan view corresponding to Fig. 2;

Fig. 4 is a vertical section through the tone-arm support, showing the connection

between the tone-arm and the stop mechanism;

Fig. 5 is a perspective view of the automatic stop mechanism; and

Fig. 6 is a drawn-out perspective view.

Referring to the drawings, wherein like reference numerals designate like parts, 10 is the usual or any suitable motor-board through which projects a spindle 11 on which is mounted a rotating element or turn-table 12 carrying a sound-record 13, said motor-board being carried by any suitable casing 65 or support.

The spindle 11 projects through the top plate 14 of a casting in which is mounted any suitable motor, such as a spring motor 15, which may be wound in the usual manner 70 by a handle 16. The spindle is rotated from the motor 15 through any suitable connections. As here shown a gear 16' on the motor shaft drives a pinion 17 on a counter-shaft 18 through suitable gear connections, 75 and a bevel gear 19 on the counter-shaft 18 meshes with a bevel gear 20 (Fig. 3) on the lower end of the spindle 11. This spindle has also mounted thereon, in the form shown, a worm-gear 21 (Fig. 5) which meshes with 80 a worm 22 on a governor-shaft 23 carrying the usual governor balls 24, and also having mounted thereon a brake disk 25 with which are associated the usual or any suitable braking pads 26. These pads may be moved 85 into and out of engagement with the brake disk 25 to control the speed of rotation of the turn-table by an arm 27 (Fig. 2) associated with a scale 28, said arm being suitably connected to a pivoted lever 29 (Fig. 90 3) on which is mounted the arm 30 carrying the brake pads 26.

The motor-board 10 is shown provided with a perforated ear 31 on which is mounted a hollow support 32 for the tone-arm or travelling element 33, carrying at one end the usual sound-box 34 provided with a needle 35 that engages the record groove in the disk 13, by which engagement the tone-arm is fed across the sound-record in a manner well understood in the art.

Secured to the tone-arm 33 and extending downwardly through the support 32, in the form shown, is a tubular member 36 to which is frictionally secured in any suitable manner an arm 37. As here illustrated, this arm

is provided at one end with an eye or opening through which the tubular member 36 passes; and annular felt washers 38 and 39 contact on either side with the arm 37 adjacent said opening (Fig. 4). These felt washers are held in place by metallic washers 40 and 41, the latter being provided with lugs 42 that engage in recesses 43 in the tubular member 36, whereby washer 41 is 5 locked to said tubular member by a bayonet-joint connection. A spiral spring 44 engages around the tubular member 36, one end of said spring engaging washer 40 and the other end a washer 45, said washers and 10 spring being housed in a recess 46 provided in said support 32.

The free end of said arm 37 is shown provided with a downwardly projecting finger 47 that engages in a bifurcated extremity 48 20 of an oscillatory lever 49 pivoted at 50 in a bracket member 51 carried by an angle-piece 52 secured to the casting 14 in any suitable manner, as by screws 53 (Fig. 4). It will be observed that, as the travelling element 25 or tone-arm is fed across the record in a clockwise direction, the arm 37 will move in the same direction, and the right-hand end of the lever 49, as seen in Fig. 5, will be moved anti-clockwise as far as it can go, 30 the action of the tone-arm tending to maintain the arm in this position. The movement of the lever 49 toward the right is limited by suitable means carried by an oscillatory member or arm 54 which is pivoted 35 on a screw 55 carried by the angle-piece 52. This pivoted member or carrying arm 54 is moved or vibrated to and fro in any suitable manner. As here shown, said arm is provided with an offset or hooked extremity 40 56 which engages a cam 57 mounted on a stub-shaft 58 carried by the casting 14, said cam being associated and movable with a gear 59 in mesh with a pinion surface 60 on the spindle 11. This cam acts to move the 45 pivoted member 54 in one direction; and a spring 61', one end of which is connected to said member and the other end of which is anchored to the casting 14, is preferably employed to return the pivoted member or arm 50 to its original position.

The particular means here shown which limits the movement of the right-hand end of the pivoted lever 49 under the influence of the travelling element or tone-arm is a 55 lug 61 carried by the pivoted member 54 and, during the reproduction of the sound-record, the lever 49 continually contacts with said lug, so that said lever is positively but intermittently moved in one direction by 60 and with the pivoted member 54, and is moved intermittently in the opposite direction, and held against the lug 61, by the operation of the moving tone-arm.

Upon the cessation of movement of the 65 tone-arm, the pivoted member 54 moves the

lever 49 into engagement with the means, whether mechanical or electrical, that effect the stopping of the turn-table. As here shown, the means are mechanical and embody a brake that operates on the brake 70 disk 25.

The particular embodiment shown of this aspect of the inventive idea is best illustrated in Figs. 2, 5 and 6. As there shown, an arm 62 which, for convenience, is herein designated as a "contact" arm, is pivoted on the screw 55 below the member 54, a washer 63 surrounding said pivot being interposed between the members 54 and 62, and a washer 64 being interposed between 80 the contact member 62 and the angle-piece 52. The free end 62' of this contact lever is moved toward the right (Figs. 2 and 5) by a spring 65 one end of which is secured to the extremity 62', and the other end of 85 which is anchored to the top 14 of the motor casting; and, during reproduction of the sound-record, the end of this lever engages in an annular groove 66 just below the head 67 of a braking member 68, and holds said member out of engagement with the brake disk 25. When said extremity is removed from the groove, the brake member 68 is pressed down under the action of the spring 84, the lower end thereof then engaging the 95 periphery of the brake disk 25 (as shown in dotted lines in Fig. 1) and stopping the machine.

Any suitable means are carried by the pivoted member 54 for engaging the lever 100 49 with the contact member 62 for the purpose of removing the free end 62' of said contact member from the groove 66 to stop the machine, and as here shown these means consist of a pivoted trip or latch 69 mounted 105 in lugs 70 and 71 formed integrally with the member 54. This trip or latch is provided with a downwardly projecting nose 72 which, when the tone-arm and the lever 49 have ceased to move, engages a slot 73 in 110 lever 49 by gravitational action whereby the right-hand end of said lever is subsequently moved into engagement with a part of the contact member 62, moving its extremity 62' out of groove 66 on the brake member 68. 115 In order to compensate for wear, and to secure exact and effective adjustment of the members, the part of the contact member 62 engaged by the arm 49 is shown as an independent slotted angle-piece which is provided with an upwardly projecting portion 74 with which the end of the lever 49 contacts, said angle-piece being adjustable toward and from said lever 49 by means of a screw and slot connection, the screws 75 being carried 120 by the member 62 and the slot 76 being provided in said angle-piece.

Immediately after the lever 49 has displaced the contact member 62 and released the brake 68, a stop 77 mounted on 130

the casting 14 engages a downwardly projecting tail 78 carried by the trip or latch 69 and rocks the nose 72 of said latch out of engagement with the notch 73, whereupon 5 said nose falls into engagement with the top surface of the lever 49, where it remains until a new reproduction has been effected and the tone-arm and the lever 49 have again come to rest, at which time it will 10 again engage slot 73 and move the lever 49 to perform again its stopping function. In order to insure the proper vertical positioning of the end 62' of the contact member so that it will engage groove 66 in the brake- 15 member 68 when the latter has been elevated, a pin 79 is carried by the casting 14 and is positioned immediately below the extremity 62'.

If desired, the automatic stop mechanism 20 described may be associated with automatic start mechanism; that is to say, with mechanism associated with the tone-arm such that, when the latter is moved into position at the commencement of the record, the rotation 25 of the turn-table will be automatically effected. The start mechanism herein shown is, however, of the manual type, and means are provided for elevating the brake-member 68 out of engagement with the disk 25 30 so that the turn-table will commence rotating. As here shown (Figs. 1 and 2), said means consist of a lever 80 pivoted at 81 to the underside of the motor-board 10, this lever carrying at one end a pin 82 that projects 35 upwardly through an opening in the motor-board. A button or head 83 is carried by said pin for depressing the near end of said lever and elevating the far end thereof. The far end of said lever carries a leaf 40 spring 84 one end of which is fixedly secured to said lever, and the other end of which engages the underside of the motor-board 10, the tendency of this spring being to force 45 downward that end of the lever associated with the brake member 68. This lever 80 engages said brake member 68 in any suitable manner, as here shown the extremity thereof engaging in groove 66 in which the extremity 62' of the contact member 62 also 50 engages when the brake member 68 has been elevated. It will be understood that the elevation of the brake member 68 is effected by simply pressing on the head or button 83.

55 The operation of the device is as follows:

When reproduction is being effected, the parts are in the position shown in Fig. 2, the latch 69 being out of engagement with slot 73. The cam 57 rotates with gear 59 60 and moves the pivoted member or carrying arm 54 in one direction. The lug 61 on said member engages the edge of lever 49 and forces said lever to participate in the movement of member 54, notwithstanding the action 65 of the moving tone-arm tending to

move the lever 49 in the opposite direction. The member 54 is moved by spring 61' in a direction opposite to that of its movement by the cam 57 as soon as the cutaway portion of the cam is presented to the member 54; and the action of the moving tone-arm on the lever 49 holds it in engagement with lug 61 at this time. The member 54 and lever 49 continue to move back and forth as a unit so long as the tone-arm continues to move across the record but, when the latter stops, the tendency of the tone-arm to move the lever 49 against the lug 61 and away from the latch 69 is removed, and said lever no longer follows member 54 in its anti-clockwise movement. The pivoted member 54, however, being driven from the motor, continues to move and, as soon as the cutaway portion of the cam presents itself to member 54, the spring 61' moves said member 54 and latch 69 toward the now-stationary lever 49, whereupon the nose 72 of latch 69 drops into slot 73. Thereafter the lever 49 is moved toward the part 74 of contact member 62 by cam 57 acting through pivoted member 54, the contact member is displaced, and brake member 68 engages brake disk 25 and stops the rotation of the turn-table. Practically coincident with the dropping of the brake member the latch 69 is 95 rocked out of the slot 73 whereupon, as soon as the brake member 68 is elevated by lever 80, so that the extremity 62' of contact member 62 can engage groove 66 to hold the brake member away from the brake disk, 100 spring 65 then moving member 62 and, through member 74, lever 49 to withdraw slot 73 from under the nose of latch 69, the parts are again in position for the operation of the automatic stop mechanism.

105 While for the purpose of enabling the invention to be understood, the illustrated embodiment has been herein described with some particularity as to detail of construction and form and arrangement of parts, 110 it is to be understood that the invention is not limited to such details, since various modifications in such details may be resorted to without departing from the spirit of the invention, and the claims hereto appended are intended to cover such modifications and variations as fall within the spirit of the invention herein described.

115 What is claimed is:—

120 1. In combination, a travelling element, a lever, a frictional connection between said traveling element and said lever, a carrying arm, means between said lever and arm whereby the former is moved by the latter, a rotating element, means moving said arm 125 from said rotating element, a contact arm, means controlled by said contact arm for stopping the movement of said rotating element, and means mounted on said carrying arm and engaging said lever with said 130

contact arm upon the cessation of movement of said travelling element.

2. In combination, a travelling element, a pivoted lever, connections therebetween tending to maintain said lever in a definite relation during the movement of said element, a rotating element, a member moved therefrom and carrying said lever therewith, a contact member, means controlled by said contact member for stopping the movement of said rotating element, and means whereby said lever engages said contact member upon the cessation of movement of said travelling element.
- 15 3. In combination, a rotating element, a member moved therefrom, a travelling element, a pivoted lever, a frictional connection between said traveling element and said lever, positive connection between said lever and member for moving the former with the latter in one direction, a contact member, means controlled by said contact member for stopping the movement of said rotating element, and means engaging said lever and contact member upon the cessation of movement of the travelling element.

4. In combination, a rotating element, a member moved therefrom, a travelling element, a pivoted lever, a frictional connection between said traveling element and said lever, positive connections between said lever and member for moving the former with the latter in one direction, a contact member, means controlled by said contact member for stopping the movement of said rotating element, and means carried by said first-named member and operatively engaging said lever upon the cessation of movement of the travelling element to move said lever into engagement with said contact member.

- 45 5. In combination, a rotating element, a pivoted member moved thereby, a travelling element, a pivoted lever mounted in a vertical plane passing through said pivoted member, a frictional connection between said traveling element and said lever, positive connections between said lever and member for moving the former with the latter in one direction, a contact member, means controlled by said contact member for stopping the movement of said rotating element, and means carried by said pivoted member to move said lever into engagement with said contact member upon the cessation of movement of the travelling element.

- 60 6. In combination, a rotating element, a member moved thereby, a travelling element, a pivoted lever, a frictional connection between said traveling element and said lever, positive connections between said lever and member for moving the former with the latter in one direction, a contact member means controlled by said contact member for stopping the movement of said rotating element, a latch carried by said first-

named member and operatively engaging said lever to move it into engagement with said contact member upon the cessation of movement of the travelling element, and means for tripping said latch out of operative engagement with said lever.

7. In combination, a rotating element, a member moved thereby, a travelling element, a pivoted lever, a frictional connection between said traveling element and said lever, positive connections between said lever and member for moving the former with the latter in one direction, a contact member, means controlled by said contact member for stopping the movement of said rotating element, means for adjusting the relation between said contact member and lever, and means for engaging said lever and contact member upon the cessation of movement of the travelling element.

8. In combination, a travelling element, an arm frictionally connected thereto and movable therewith, a pivoted lever operatively connected to said arm, a rotating element, a cam driven thereby, a pivoted member moved in one direction by said cam, means between said member and lever whereby they move together, a contact member, means controlled by said contact member for stopping the movement of said rotating element, and a trip carried by said pivoted member and acting to engage said lever with said contact member upon cessation of movement of said travelling element.

9. In combination, a travelling element, an arm frictionally connected thereto and movable therewith, a pivoted lever operatively connected to said arm, a rotating element, a cam driven thereby, a pivoted member moved in one direction by said cam, a spring moving said member in the opposite direction, means between said member and lever whereby they move together, a pivoted spring-pressed contact member, means controlled by said contact member for stopping the movement of said rotating element, and a trip carried by said pivoted member and acting to engage said lever with said contact member upon cessation of movement of said travelling element.

10. In combination, a rotating element, a pivoted member moved thereby, a travelling element, a pivoted lever, a frictional connection between said traveling element and said lever, positive connections between said lever and member for moving the former with the latter in one direction, a contact member, a brake element controlled thereby, and means engaging said lever and contact member to render said brake operative upon the cessation of movement of said travelling element.

11. In combination, a travelling element, a pivoted member, a frictional connection between said traveling element and said member, said element tending to move said mem-

- ber in one direction during the normal movement of said element, a rotating element, a carrying member moved thereby, positive connections between said carrying member 5 and pivoted member whereby the latter is moved in a direction opposite to that of its movement by the travelling element, means for stopping the rotating element, and means engaging said pivoted member and moving 10 it into engagement with said stopping means to effect the stopping action when the travelling element ceases to move.
12. In combination, a travelling element, a pivoted member, a frictional connection between said traveling element and said member, said element tending to move said member in one direction during the normal movement of said element, a rotating element, a carrying member moved thereby, positive 15 connections between said carrying member and pivoted member whereby the latter is moved in a direction opposite to that of its movement by the travelling element, means for stopping the rotating element, and means 20 carried by said carrying member for engaging said pivoted member and moving it into engagement with said stopping means to effect the stopping action when the travelling element ceases to move.
- 30 13. In combination, a rotating element and a travelling element, a member moved by the travelling element, a second member oscillated by the rotating element, connections between said members whereby they move as a unit in one direction during the normal movement of said travelling element, stopping mechanism, and means for moving the first-indicated member a supplemental distance into engagement with said stopping 35 mechanism upon the stopping of said travelling element.
14. In combination, a rotating element and a travelling element, a member continuously in operative relation with the travelling element, a second member continuously in operative relation with the rotating element, connections between said members whereby they move as a unit in one direction during the normal movement of said travelling element, stopping mechanism, and means carried by said second member for moving the first-indicated member a supplemental distance into engagement with said stopping mechanism upon the stopping of said travelling 40 element.
- 55 15. In combination, a rotating element and a travelling element, a member frictionally driven from and continuously in operative relation with the travelling element, a second member continuously in operative relation with the rotating element, connections between said members whereby they move as a unit in one direction during the normal movement of said travelling element, stopping mechanism, and means for moving the 60 65
- first-indicated member a supplemental distance into engagement with said stopping mechanism upon the stopping of said travelling element.
16. In combination, a rotating element and a travelling element, a member frictionally driven from and continuously in operative relation with the travelling element, a second member continuously in operative relation with the rotating element, connections between said members, stopping mechanism, and means for moving the first-indicated member into engagement with said stopping mechanism upon the stopping of said travelling element. 70
17. In combination, a rotating element, a travelling element, a member moved by the travelling element, a member oscillated by the rotating element, means whereby said members move as a unit during the normal movement of said travelling element, stopping mechanism, and means for moving said first-named member a supplemental distance into engagement with said stopping mechanism upon the stopping of said traveling element. 80
18. In combination, a rotating element, a traveling element, a lever moved by the travelling element, an arm oscillated by the rotating element, means whereby said lever and arm move as a unit during the normal movement of said traveling element, stopping mechanism, and means for moving said lever a supplemental distance into engagement with said stopping mechanism upon the stopping of said traveling element. 85
19. In combination, a rotating element, a traveling element, a member oscillated by one of said elements, a second member maintained in cooperative relation with said first-named member and oscillating therewith so long as the traveling element continues its normal movement, stopping mechanism, and means for moving one of said members a supplemental distance into engagement with said stopping mechanism upon the stopping of said traveling element. 90
20. In combination, a rotating element, a traveling element, a member oscillated by one of said elements, a second member maintained in cooperative relation with said first-named member and oscillating therewith so long as the traveling element continues its normal movement, stopping mechanism, and means for moving said second-named member a supplemental distance into engagement with said stopping mechanism upon the stopping of said traveling element. 95
21. In combination, a rotating element, a traveling element, a member oscillated by one of said elements, a second member maintained in cooperative relation with said first-named member and oscillating therewith so long as the traveling element continues its normal movement, stopping mechanism, and means for moving the 100 110 115 120 125 130

anism, and means whereby said oscillating member moves said second-named member a supplemental distance into engagement with said stopping mechanism upon the stopping 5 of said traveling element.

22. In combination, a rotating element, a traveling element, a member oscillated by the rotating element, a second member operatively connected to the traveling element 10 and maintained in cooperative relation with said first-named member and oscillating therewith so long as the traveling element continues its normal movement, stopping mechanism, and means for moving said second-named member a supplemental distance 15 into engagement with said stopping mechanism upon the stopping of said traveling element.

23. In combination, a rotating element, a traveling element, a member oscillated by the rotating element, a second member operatively connected to the traveling element and maintained in cooperative relation with said first-named member and oscillating 25 therewith so long as the traveling element continues its normal movement, stopping mechanism, and means whereby said oscillating member moves said second-named member a supplemental distance into engagement 30 with said stopping mechanism upon the stopping of said traveling element.

24. In combination, a rotating element, a traveling element, a member oscillated by the rotating element, a second member operatively connected to the traveling element and maintained in cooperative relation with said first-named member and oscillating therewith so long as the traveling element continues its normal movement, stopping 35 mechanism, and means whereby said oscillating member moves said second-named member a supplemental distance into engagement with said stopping mechanism upon the stopping of said traveling element, 40 and means for releasing said last-named means upon actuation of the stopping mechanism.

25. In combination, a rotating element, a traveling element, a member oscillated by the rotating element, a second member moved by the traveling element, means whereby said members move as a unit during the normal movement of the traveling element, a second means operative upon the 50 stopping of the traveling element to cause said members to move as a unit, and stopping mechanism actuated by said members when connected by said second-named means.

26. In combination, a rotating element, a traveling element, a member oscillated by the rotating element, a second member moved by the traveling element, means whereby said members move as a unit during the normal movement of the traveling 65 element, a second means carried by said os-

cillating member and operative upon the stopping of the traveling element to cause said members to move as a unit, and stopping mechanism actuated by said members when connected by said second-named 70 means.

27. In combination, a rotating element, a traveling element, a member oscillated by the rotating element, a second member moved by the traveling element, means whereby said members move as a unit during the normal movement of the traveling element, a latch carried by said oscillating element and operative upon the stopping of the traveling element to connect said members, and stopping mechanism actuated by said members when connected by said latch. 75

28. In combination, a rotating element, a traveling element, a member oscillated by the rotating element, a second member moved by the traveling element, means whereby said members move as a unit during the normal movement of the traveling element, a latch carried by said oscillating member and operative upon the stopping of the traveling element to connect said members, stopping mechanism actuated by said members when connected by said latch, and means to release said latch upon actuation 80 of said stopping mechanism. 90

29. In combination, a rotating element, a traveling element, a member moved by said traveling element, means moved to and fro by said rotating element and moving said member supplementally upon the stopping 100 of said traveling element, and stopping mechanism operated by said supplemental movement of said member.

30. In combination, a rotating element, a traveling element, a member moved by said traveling element, a second member oscillated by said rotating element and moving said first-named member supplementally upon the stopping of said traveling element, and stopping mechanism operated by said supplemental movement of the first-named member. 105

31. In combination, a rotating element, a traveling element, a member moved by said traveling element, a second member oscillated by said rotating element, means carried thereby for moving said first-named member supplementally upon the stopping of said traveling element, and stopping mechanism operated by said supplemental movement of 110 the first-named member. 115

32. In combination, a rotating element, a traveling element, a member and driving connections therefor operatively related to said traveling element, a second member and driving connections for oscillating the same operatively connected to said rotating element, stopping mechanism, and means for moving said first-named member a supplemental distance into engagement with said 125 130

stopping mechanism upon the stopping of the traveling element.

33. In combination, a rotating element, a traveling element, a member and driving connections therefor operatively related to said traveling element, a second member and driving connections for oscillating the same operatively connected to said rotating element, stopping mechanism, and means carried by said second-named member for moving said first-named member a supplemental distance into engagement with said stopping mechanism upon the stopping of the traveling element.

15 34. In combination, a rotating element, a traveling element, a member moved by the traveling element, a second member moved to and fro by the rotating element, means carried by said second member for moving 20 said first member supplementally upon the stopping of the traveling element, and stop mechanism operated by said supplemental movement of said member.

25 35. In combination, a rotating element, a member driven thereby, a traveling element, a second member, connections between said traveling element and said second member to maintain said second member in coacting relation with said first member, stop mechanism comprising a contact member, and means carried by said first member to move said second member into engagement with said contact member upon the cessation of movement of the traveling element.

30 36. In combination, a rotating element, a traveling element, an oscillating member, a second member operatively connected to the traveling element and maintained in co-operative relation with said oscillating member and oscillating therewith so long as the traveling element continues its normal movement, and stop mechanism engaged and actuated by one of said members upon the stopping of the traveling element.

45 37. In combination, a rotating element, an oscillating member driven thereby, a traveling element, an oscillating member operatively connected to said traveling element and maintained in oscillation so long as the traveling element continues its normal movement, and stop mechanism operated by one of said members upon the stopping of the traveling element.

55 38. In combination, a rotating element, an oscillating member driven thereby, a traveling element, an oscillating member operatively connected to said traveling element and maintained in oscillation so long as the traveling element continues its normal movement, and stop mechanism engaged by the first oscillating member and operated by said second oscillating member upon the stopping of the traveling element.

65 39. In combination, a rotating element, a traveling element, a member moved intermit-

tently in one direction by the traveling element, an oscillatory member operatively connected with the rotary element and moving said first member intermittently in the opposite direction, means whereby said first member is supplementally moved in the second-named direction when the traveling element ceases its travel, and stop mechanism operated by said supplementary movement of said first member.

75 40. The combination with a phonograph and its motor, of a vertically reciprocating plunger, adapted at its lower end to brake directly upon a moving part of the motor, means for supporting the plunger in its elevated position and out of braking relation with the motor, and means adapted, through co-operation with the tone-arm, to release the plunger.

80 41. The combination with a phonograph and its motor, of a vertically reciprocating plunger at one side of the turn-table support, and adapted at its lower end, to brake upon a moving part of the motor, means for supporting the plunger in its elevated position and out of braking relation with the motor, and means, adapted through co-operation with the tone-arm, to release the plunger.

85 42. The combination with a phonograph and its motor, of a vertically reciprocating plunger adapted at its lower end to brake upon a moving part of the motor, means adapted to permit the manual lifting of the plunger to move it out of braking relation with the motor, releasable means adapted to retain the plunger in elevated position, spring means adapted to lower the plunger to braking position when released, and means adapted, through co-operation with the tone-arm, to effect the release of the plunger.

90 43. The combination with a phonograph and its motor, of a vertically reciprocating plunger, means at its lower end adapted to brake upon a moving part of the motor, means for supporting the plunger in its elevated position and out of braking relation with the motor, and automatic means adapted, through co-operation with the tone-arm, to release the plunger when the tone-arm ceases to traverse the record.

95 44. The combination with a phonograph and its motor, of a vertically reciprocating plunger at one side of the turn-table support and adapted at its lower end to brake upon a moving part of said motor, means for supporting the plunger in its elevated position and out of braking engagement with the motor, and means carried by the tone-arm for releasing said plunger.

100 45. The combination with a phonograph and its motor, of a vertically movable plunger at one side of the turn-table support and adapted at its lower end to brake upon a

moving part of said motor, means carried by the motor-board for supporting the plunger in its elevated position and out of braking engagement with the motor, and means carried by the tone-arm for releasing said plunger.

46. The combination with a phonograph and its motor, of a vertically movable plunger at one side of the turn-table support and adapted at its lower end to brake upon a moving part of said motor, an oscillating plate carried by said motor-board and engaging and adapted to support the plunger in its elevated position and out of braking engagement with the motor, and means carried by the tone-arm for oscillating said plate to release the said plunger.

47. The combination with a phonograph and its motor, of a vertically movable plunger at one side of the turn-table support and adapted at its lower end to brake upon a moving part of said motor, means carried by the motor-board for supporting the plunger in its elevated position and out of braking engagement with the motor, an arm positioned on the motor-board and adapted to operate said latter means to release the plun-

ger, and means carried by the tone-arm for operating said arm.

48. The combination with a phonograph and its motor, the latter comprising a governor-disk, of a plunger adapted to reciprocate at one side of the turn-table support and at its lower end to brake upon said disk, means for reciprocating the plunger vertically away from said disk, means for supporting the plunger in its raised inoperative position, and means carried by the tone-arm for operating said latter means to release said plunger and permit it to drop and resume braking engagement with said disk.

49. In combination, a rotating element, a traveling element, a member moved by the traveling element, another member oscillated by the rotating element, and means for obtaining supplemental movement of the first-named member on the stopping of the traveling element and of using this supplemental movement to stop the rotating element.

In testimony whereof I have signed this 50 specification.

LOUIS G. LARSEN.
